COMBINED COOLER AND BRACKETED SUPPORT

Ben B. Brooks, 5031 Lyndale Ave. S., Minneapolis, Minn.

Filed Feb. 3, 1960, Ser. No. 59,247

Term of patent 7 years

(Cl. D67—4)

Fig. 3

Fig. 4

Fig. 5

FIG. 1 is a view in side elevation of a combined cooler and bracketed support showing my new design;

FIG. 2 is a view in side elevation thereof of the side opposite that shown in FIG. 1;

FIG. 3 is a view in front elevation thereof;

FIG. 4 is a view in rear elevation thereof; and

FIG. 5 is a view in top plan thereof.

The bottom is substantially plain except for the transverse bars of the bracketed support as indicated in the drawing views.

I claim:

The ornamental design for a combined cooler and bracketed support, as shown and described.
